UNITED STATES PATENT OFFICE.

CLARE H. DRAPER, OF HOPEDALE, MASSACHUSETTS, ASSIGNEE TO HOPEDALE MANUFACTURING COMPANY, OF MILFORD, MASSACHUSETTS, A CORPORATION OF MASSACHUSETTS.

SHUTTLE-BOX TENSION-CONTROLLING MECHANISM FOR LOOMS.

Application filed July 11, 1922. serial No. 574,212.

To all whom it may concern:

Be it known that I, CLARE H. DRAPER, a citizen of the United States, residing at Hopedale, in the county of Worcester and State of Massachusetts, have invented certain new and useful Improvements in Shuttle-Box Tension-Controlling Mechanism for Looms; and I do hereby declare the following to be a full, clear, and exact description of the invention, such as will enable others skilled in the art to which it appertains to make and use the same.

The present invention relates to an improvement in shuttle box tension controlling mechanism for looms.

It has been proposed to provide a loom with mechanism for varying the resistance of the shuttle box to the entrance of the shuttle by the use of a cam and connections operating as the lay moves back and during the time the shuttle is to start on its excursion, so that the pressure on the shuttle is at first least, and then gradually increases until it reaches a maximum at the rear position of the lay, then gradually becoming less and less during the forward movement of the lay until at the expiration of the time when the shuttle must have completed its excursion the shuttle is held in the box by the light pressure of the binder, so that when the shuttle is finally boxed it is lightly held. In such construction the binder lever forming part of the protector mechanism was provided with a roll to engage a cam supported on the loom frame the contour of which with relation to the normal path of motion of the roll was such as to secure the results stated.

The object of the present invention is to produce an improved construction of mechanism for controlling the shuttle box resistance during the movements of the lay, and to this end the present invention consists in the shuttle box tension controlling mechanism hereinafter described and particularly defined in the claims.

In the accompanying drawings illustrating the preferred form of the invention, Fig. 1 is an end elevation of a loom with the shuttle box shown in section; Fig. 2 is a plan of the shuttle box; Fig. 3 is a detail hereinafter referred to; and Fig. 4 is a diagram hereinafter referred to.

The illustrated embodiment of the inven-

tion is described as follows: The lay 1, actuated by the pitman 2 connected to the crank 3 of the lay shaft 4, are of the usual construction. The front 5 of the shuttle box is fixed, and the binder 6 pivoted at 7 comprises the rear of the shuttle box. The shuttle 8 is shown in the box. To the rear of the binder 6 is attached a clevis 9, to which the eye 10 of the rod 11 is secured by means of the pin 12. The rear end of the rod is supported on a stationary part of the loom, a bracket 13 being provided for this purpose, see Fig. 3. The bracket receives the sleeve 14 which is secured in the bracket by means of the set screw 15. A nut 16 is secured to the sleeve and provides means for turning the sleeve when the set screw is released. The forward end of the sleeve 14 is provided with two inwardly projecting teeth 17 which engage the spring 18. This spring 18 encircles the rod 11, and at its forward end takes against the washer 19, which is secured in place by a nut 20 and lock nut 21, which provide a second means for adjusting the pressure exerted by the spring. The other means for adjusting the pressure exerted by the spring is the rotatable sleeve 14. By screwing the sleeve up the spring less pressure will be exerted by the spring on the rod, and therefore less pressure will be exerted on the binder 6.

It will be observed that with a given position of the sleeve 14 on the spring 18, an adjustment of the set nuts 20-21 may be made to determine the pressure exerted by the binder on the shuttle. With such adjustment there will be a certain length of spring in use. Now retaining the front adjustment fixed, by screwing the sleeve 14 up the spring and moving such sleeve forward in the bracket 13 to the extent to which it is screwed upon the spring, a less length of spring may be employed and with the same pressure exerted on the binder at its forward position the pressure on the binder will be greater in the rearward position of the lay because a shorter length of spring will have been compressed. The two adjustments therefore, are used, the front adjustment to regulate the minimum pressure on the binder (that is while the lay is in its forward position) and the rear adjustment to regulate the length of spring to be employed. It will be apparent that in

this way with a given pressure on the lay in forward position, the pressure on the binder at rearward position may be made greater or less without change of the pressure at the forward position, and vice versa.

The pick of the shuttle takes place on the back stroke of the lay at the top center and the earliest that the shuttle can box is at the back center, so that the position of the lay 15 determines the tension on the shuttle as it enters the box. If it enters as early as the back center it encounters a maximum resistance—if it enters later because of delayed pick or weak pick it encounters less and less resistance as the lay moves forward. By changing the spring adjustments the shuttle box resistance may be changed. Thus in Fig. 4 is shown a diagram illustrative of variations in box resistances secured by different 20 adjustments. A point on one of the curves represents (1) the pressure on the box by its height above the datum line and (2) the angular position of the crank by its distance from the zero point. Curve A shows the 25 conditions of box pressure where the pressure on the box is a certain amount at the front center and increases to a greater amount at the back center and decreases again to the former amount at the front center. The pick takes place, say, at the top center, and the shuttle arrives at the opposite box between the back center and the bottom center—the later it arrives the less the pressure there is on it. Curve B is one with the 30 same front center pressure as A but with a higher back center pressure—suitable for a higher speed loom than curve A. Curve C is one with a higher front center pressure and a lower back center pressure—suitable for 35 a lower speed or lighter shuttle loom. From the foregoing it will be seen that the pressure on the shuttle may be adjusted at either end of the lay stroke to different amounts independently of adjustment of the pressure 40 at the opposite end of the lay stroke.

In the position of the parts illustrated in Fig. 1 with the lay at its back center, the spring will be in its condition of greatest compression, and as the lay moves forward, the 45 pressure exerted by the spring on the binder will be less and less, and a minimum at the front center. Ordinarily the shuttle will be picked at the top center, and as the lay approaches the back center, the pressure on the 50 shuttle binder will be greater and greater. Ordinarily the shuttle will reach the opposite box between 210° and 240° of crank position, assuming zero crank position to be at front center. If, however, the shuttle is 55 picked with greater speed, it will be received in the box at an earlier time, and the tension on the shuttle will be greatest at the back center. If the shuttle reaches the opposite box after this point, the tension will be correspondingly less, so that in case of a light

pick and a slow moving shuttle, the tension on the shuttle box will be correspondingly decreased. It will thus be apparent that from front center to back center the pressure on the shuttle box will gradually be increased, and from back center to front center the pressure will gradually be decreased.

Having thus described the invention, what is claimed is:

1. Shuttle box tension controlling mechanism for looms having, in combination, a lay, a shuttle box carried by the lay and provided with a binder on the rear side of the box, a rod attached at its forward end to the binder and slidably supported at its 80 rear end on a stationary part of the loom, and a yielding contrivance acting on the rod to apply increasing resistance to its rearward movement with the backward movement of the lay. 85

2. Shuttle box tension controlling mechanism for looms having, in combination, a lay, a shuttle box carried by the lay and provided with a binder on the rear side of the box, a rod attached at its forward end to the binder and slidably supported at its 90 rear end on a stationary part of the loom, and a yielding contrivance acting on the rod to apply increasing resistance to its rearward movement with the backward 95 movement of the lay, and decreasing pressure on the forward movement of the lay.

3. Shuttle box tension controlling mechanism for looms having, in combination, a lay, a shuttle box carried by the lay provided with a binder on the rear side of the box, a rod attached at its forward end to the binder and slidably supported at its 100 rear end on a stationary part of the loom, and a yielding contrivance acting on the rod to apply increasing resistance to the 105 binder from the front center to the back center.

4. Shuttle box tension controlling mechanism for looms having, in combination, a 110 lay, a shuttle box carried by the lay and provided with a binder on the rear side of the box, a rod attached at its forward end to the binder and slidably supported at its rear end on a stationary part of the loom, and a yielding contrivance acting on the rod to apply decreasing resistance to its rearward movement from the back center 115 to the front center.

5. Shuttle box tension controlling mechanism for looms having, in combination, a 120 lay, a shuttle box carried by the lay and provided with a binder on the rear side of the box, a rod attached at its forward end to the binder and slidably supported at its 125 rear end on a stationary part of the loom, a helical compression spring mounted on the rod, its forward end engaging a part of the rod, and its rearward end engaging a stationary part of the loom to apply increas- 130

ing resistance to the binder as the shuttle moves rearwardly.

6. Shuttle box tension controlling mechanism for looms having, in combination, a lay, a shuttle box carried by the lay and provided with a binder on the rear side of the box, a rod attached at its forward end to the binder and slidingly supported at its rear end on a stationary part of the loom, an abutment for the forward end of the spring secured to the rod, and a sleeve receiving the spring at its rear end which is rotatably supported on a stationary part of the loom, such sleeve being provided with teeth engaging the spring coils adapted to be screwed forward or back on the spring to regulate the tension thereof, and means for locking the sleeve in adjusting position.

7. Shuttle box tension controlling mechanism for looms having, in combination, a lay, a shuttle box, and a friction device acting on the shuttle in its box to retard its motion, and yielding means acting permanently on the friction device with varying pressure depending upon the position of

the lay to increase the pressure as the lay approaches the back center and to decrease the pressure as the lay recedes therefrom.

8. Shuttle box tension controlling mechanism for looms having, in combination, a lay, a shuttle box, a friction device for retarding the shuttle as it enters the box, yielding means acting on the friction device with varying pressure depending upon the position of the lay to decrease the pressure as the lay moves forwardly, and adjustments for the yielding means to increase or decrease the pressure at each end of the lay stroke independently of modification of the pressure at the other end of the lay stroke.

9. Shuttle box tension controlling mechanism for looms having, in combination, a lay, a shuttle box, a friction device for retarding the shuttle as it enters the box, and yielding means permanently acting on the friction device with varying pressure depending upon the position of the lay to decrease the friction exerted by the device as the lay recedes from the back center.
